[57] CLAIM

The ornamental design for a collapsible rack for clothes hangers, bola ties or jewelry items, as shown and described.

DESCRIPTION

FIG. 1 is a top, front perspective view of a collapsible rack for clothes hangers, bola ties or jewelry items showing my new design;

FIG. 2 is a bottom, rear perspective view thereof;

FIG. 3 is a partial top view of FIG. 1;

FIG. 4 is a partial rear perspective view with the arm in its stored position;

FIG. 5 is a front perspective view with the arm in its stored position;

FIG. 6 is a top view of FIG. 5.
